GAME APPARATUS

William J. Knox, Du Bois, Pa.

Original application May 18, 1932, Serial No. 611,968. Divided and this application March 27, 1933, Serial No. 662,956

2 Claims. (Cl. 273—129)

The invention relates to an apparatus for games and constitutes a division of my Patent No. 1,906,865, dated May 2, 1933. The construction involves the use of a chute for projecting a ball or other circular shooter, and is shown as applied to a table top, but it will be understood that the chute may be used with any kind of a flat surface, whether it be with the top of the special table shown, or with a board which may be placed on a floor or table, or with the floor itself, or with the top of an ordinary table. The invention has for its principal objects, the provision of a construction particularly adapted for games, such as ten pins, and having an improved chute which may be used to discharge the balls, or discs employed at any desired speed and at any desired angle. Other objects of the invention will appear in connection with the description following and the drawings, wherein:

5 Figs. 1, 2, and 3 show the table preferably employed, Fig. 1 being a side elevation, Fig. 2 a plan view, and Fig. 3 a section on the line III—III of Fig. 2, the latter figure showing the chute which is not shown in Figs. 1 and 2. Figs. 4, 5 and 6 10 are detail views showing the adjustment for leveling the table. Fig. 7 is a detail sectional view through the edge of the table showing a modification. And Figs. 8 to 12 are detail views of the chute, Fig. 8 being a plan view, Fig. 9 a side elevation, Fig. 10 a bottom view, Fig. 11 an end view, and Fig. 12 a side elevation showing the chute in position of use.

15 The body of the table comprises the top plate or board 1, the side strips 2, 2, and the end members 3 and 4, all rigidly secured together by any suitable means. These parts are preferably all of wood. The side and end strips form stiffeners for the top plate, thus avoiding the necessity for the usual underframing, and at the same time 20 serve as the bounding strips for the balls or discs as used in the game for which the table is designed. At the four corners of the table are the metal brackets 5, 5, 5, 5 secured to the top plate and side members by screws, and in these members are pivoted the legs 6, 6, 6, 6, held in the position shown by the braces 7, 7, 7, 7 pivoted to the legs, and having their ends turned at right angles and engaging perforations in the holding brackets 8, 8, 8, 8. The features relating to the 25 folding and adjustment of the legs are described in detail and claimed in my application heretofore referred to, and therefore require no further explanation here.

The face of the plate or board may be used for 30 various games. It is marked for ten pins, as in-

dicated at 9; for checkers, as indicated at 10; and for shuffle board, as indicated at 11. The board is especially serviceable in games like ten pins, which employ balls or discs, as the side members 2, 2 and end members 3, 4 prevent the balls or other movable members used in the game from leaving the table.

If desired, the top of the table may be provided with a removable metal pan 12, as shown in Fig. 7, which may be used to protect the wood, or for the purpose of giving a differently marked or indented surface to meet the requirements of different games. Such pan may be made of aluminum or other suitable material. The legs of the table are preferably provided with the leveling devices shown in Figs. 4, 5 and 6, such devices comprising the sleeves 13, in which the members 14 are threaded. The members 14 are preferably provided with the rubber pads 15. These devices are especially useful in connection with games, such as ten pins, in which a level table surface is essential for accurate play. The sides of the table may also be provided with spirit levels 16, 20 to assist in leveling the board.

When the table is used for ten pins or similar games, the chute 17 (Figs. 8 to 12) is used. This chute is provided with a groove 18 for the ball 19, and is constructed so that any desired adjustment may be secured to give the ball the desired direction and speed of movement. A spring member 20 serves to give the ball additional impetus, such spring being shown in the dotted lines A in retracted position ready to be released. The lower side of the chute is provided with a plurality of transverse grooves 21 adapted to engage the upper edge of the end member 3. The inclination of the chute to the horizontal to control the speed of the ball may be regulated by this means. The chute may also be adjusted along the member 3, and may be tilted laterally at any desired angle, 35 due to the tapering shape of the grooves 21, as indicated in Fig. 10. The shape of the groove 18 may be modified to meet requirements in case some other form of shooter is employed. The invention is not limited to the use of a chute having the grooves 21 on its lower side, but the grooved construction is preferred, as the grooves provide a means for steadyng the device and holding it securely in position while discharging the balls or discs.

What I claim is:

1. In combination in apparatus for use with a playing surface, a supporting strip thereon and an adjustable chute having a series of transverse grooves on its lower side adapted to engage the

110

upper edge of said strip and permit the chute to be adjusted along said strip and also transversely thereof to tilt the chute to varying angles of inclination with respect to said surface.

5 2. In combination with apparatus for use, a playing surface, a supporting strip thereon, and an adjustable chute having a series of transverse grooves on its lower side adapted to engage the

upper edge of said strip and permit the chute to be adjusted along said strip and also transversely thereof to tilt the chute to varying angles of inclination with respect to said surface, said grooves tapering in width from their centers to 80 their ends to permit the chute to be tilted laterally.

WILLIAM J. KNOX.
